UNITED STATES PATENT OFFICE

LEO C. SAFIR, OF NEW YORK, N. Y.

SLIPPER-DISPLAY CONTAINER

Application filed August 30, 1928. Serial No. 302,915.

The present invention relates to shoe displaying and packaging, and is directed particularly to the provision of a device for neatly packing and displaying a pair of slippers or the like.

In displaying slippers which have relatively soft and pliable toes, it is important that the toe portions be stretched to their intended rounded shape so that the slippers will present as neat and attractive an appearance as possible. It is also desirable that slippers of this kind, especially those having uppers of cloth or felt, such for example, as bath slippers, be arranged in a neat package so that the slippers will present the same attractive appearance while the shoe is being examined by the customer as when on display in a store window or show case. Furthermore, some slippers, such for example, as mules which have no quarters, are the most attractive when only the toe portions can be seen.

In my prior Patent No. 1,598,395, granted to me on August 31, 1926, there is disclosed and claimed a slipper display support or display container for such slippers. This display and packing device is intended for use where slippers are sold in a set with other garments, for example, a bathrobe, particularly where the toe portions of the slippers are constructed of material which matches the material of the bathrobe. My prior device conceals the interiors and the soles of the slippers which are usually of contrasting color to that of the toe portions of the robe, and because of the concealment of such portions, the fact that the toe portions of the slippers and the material of the robe are made to match is made more striking.

The container of my former patent comprises a box-like structure having a bottom and side walls, and a longitudinal member disposed between the side walls and preferably secured intermediate its ends to this container. Oppositely extending tongues are formed on this longitudinal member and the two slippers of a pair are supported in telescoped relation on these tongues with their toe portions extending outwardly.

The device of my prior patent has proved

to be practical and commercially successful. However, the improved container of my present invention supports the slippers in such a way that they are even neater and more attractive in appearance than when displayed in my earlier display support. Moreover, the improved construction is such that the cost is only slightly greater.

One of the objects of my present invention is to provide a display container made of thin relatively flexible material which is so constructed that the toe portions of the slippers are supported at substantially the same level.

Another object of the invention is to provide a display container for slippers in which the central portions and interiors of a pair of slippers arranged with their toes extending in opposite directions, are well concealed, and at the same time the toe portions are supported in neat condition and clearly exposed to view.

Another object of the invention is to provide a display container which will support the toe portions of the slippers in smooth condition even though the container is made of flexible material.

In order that the invention may be clearly understood, I have illustrated by way of example one embodiment of the invention in the accompanying drawings. In these drawings,

Fig. 1 is a perspective view of the improved device for displaying and packing a pair of slippers;

Fig. 2 is also a perspective view similar to Fig. 1 with a pair of slippers placed in telescoped position within the device;

Fig. 3 is a longitudinal section taken centrally through Fig. 2;

Fig. 4 is a transverse section taken on line 4-4 of Fig. 3; and

Fig. 5 is a plan view showing the development of the blank from which the device is made.

Referring now to these drawings, the slipper display device comprises a container having side walls 10 and 11 projecting upwardly in parallel relation from a bottom 12. These side walls 10 and 11 slope away gradually from the central portion of the container to

ward each end for a purpose which will hereinafter appear. The tops of the walls are preferably joined at their central portions by a bridge member 13 which serves to tie the walls together and increase the rigidity of the container. Tongues 14 and 15 extend longitudinally between the side walls and are preferably made integral with the bridge member 13.

10 The slippers 16 and 17 are placed in telescoping relationship with one another as may be seen in Fig. 3, with their toe portions 18 and 19 respectively placed upon the tongues 14 and 15. The entire container is preferably made of relatively thin flexible material, such for example, as paste-board and consequently the weight of the slippers tends to depress the tongues from their normal horizontal position. The toe portion 18 is supported from the underside by the heel 20 of slipper 17, so that the toe 18 does not tend to fall as low as the toe 19 which is not supported in this manner.

15 In my former slipper container covered by my patent above mentioned, this depression of the toe portion of one of the slippers below that of the other has made the package unsymmetrical and thus has impaired its appearance to an undesirable extent. According to my present invention, this defect is overcome by the provision of the supports 21 and 22 at each end of the box which engage one or both of the tips of the toe portions 18 and 19 respectively, and raise them to the same elevation above the bottom 12. When the heel of the lower slipper is sufficiently thick, as shown in Fig. 3, to elevate the toe of the upper slipper to the desired extent—preferably partially above the side walls 10 and 11—the toe of the upper slipper is usually not raised any higher by support 21, but barely touches the support as shown at the left of Fig. 3. Support 21 then prevents any substantial depression of the portion of the toe that extends beyond the heel of the lower slipper. Support 22, however, elevates the toe of the lower slipper to substantially the same level as the toe of the upper slipper. It will be understood that the degree of support of the upper slipper afforded by the lower slipper and by support 21 depends to a large extent upon the position which the slippers happen to assume when they are placed in the container. In some cases the upper slipper may be almost wholly supported by the heel of the lower slipper, and in others the upper slipper may rest partly upon the lower slipper and partly upon the support 21. If the heels of the slippers are not very thick, or it is desired to raise the toes of the slippers higher above the tops of the side walls 10 and 11, then both toes rest firmly upon both of the supports 21 and 22.

20 Supports 21 and 22 thus co-operate with the tongues 18 and 19 in supporting the toes

of the slippers in a neat symmetrical position with respect to one another. It is not convenient, and tends to increase the cost of the container, to construct the tongues 14 and 15 in such a way that they will possess sufficient rigidity to support the slippers in this position by themselves. With the aid of the supports 21 and 22, however, this is accomplished without difficulty since these supports can easily and cheaply be made to have the necessary strength.

25 Even if the tongues 14 and 15, however, were so made as to support the slippers in the desired position, without the aid of the supports 21 and 22, these supports are desirable since they form a partial closure for the ends of the container which gives a more finished appearance to the display device.

30 The supports 21 and 22 each consist of an upright member 23 and a brace 24 which extends from the top of the upright inwardly and is secured to the bottom of the container. For this purpose the inner edge of the brace 24 has a projecting portion 25 having laterally extending lips 26 which pass through slits 27 in the bottom of the box and are held in place by being folded flat against the underside of the bottom, as shown in Fig. 4. This construction avoids the necessity of using an adhesive for holding the braces in place.

35 The various portions of the packing and display device described in detail above have been indicated on the development shown in Fig. 5, and by folding the blank on each of the straight dotted lines shown in this figure the container is formed. It will be noted that the overlapping margins 28 and 29 are placed respectively along the lower edge of the side wall 10, and along the side edge of the bottom 12 so that the bridge 13 is joined integrally to both of the sides 10 and 11, thus avoiding an unsightly joint at the top or exposed part of the container.

40 The tongues 14 and 15, together with the bridge portion 13, form a shoe tree for the telescoped slippers which serves to spread or stretch the material of the toe portions of the slippers and hold them in a neat, smooth condition, and at the same time conceals the interiors of the mid-sections of the slippers so that only the toe portions are visible. Moreover, the side walls 10 and 11 of the box or container are made to slope away gently from the bridge 13 towards each end, and the height of the supports 21 and 22 is such as to raise the upper part of the toe portions of the slippers slightly above the curved edges of the walls 10 and 11. This may be observed in Fig. 3 and causes the toe portions to be clearly exposed so that a considerable portion of them may be seen when the package is viewed from an angle, as well as when it is viewed from directly above.

45 In order to stretch the toe portions of the

slippers both crosswise and lengthwise, the tongues 14 and 15 in my improved container have their side edges rounded, as indicated at 30 and they are also scored along curved lines which extend longitudinally of the tongues in approximately parallel relationship with the side margins 30. These scorings are indicated by the curved dotted lines shown in Figs. 1, 2 and 5. These scorings are made from the upper surfaces of the tongues and because of their particular shape, cause the upper surfaces of the tongues to accurately conform to the interior surface of the toes of the slippers, as indicated in Fig. 4. Because 15 of the curved edges of the tongues and these scorings, the outer ends 31 of each tongue extend, as shown in Fig. 3, in close proximity to the ends of the toe portions 18 and 19 so that the toe portions are supported throughout 20 substantially their entire length.

Furthermore, when the weight of the toe portions of the slippers depresses the tongues 14 and 15 until the toes rest on the supports 21 and 22, this depression of the tongues causes 25 the curved side margins to press against the sides of the toe portion, as shown in Fig. 4. This stretches the toes crosswise and draws the material of the slippers against the smoothly rounded surfaces of the tongues.

30 What I claim as new and desire to secure by Letters Patent of the United States is:

1. A display container for slippers or the like comprising a body portion including a bottom and side walls, a longitudinal member 35 between the side walls and formed with oppositely extending tongues for receiving the toe portions of a pair of slippers and supporting said slippers in telescoped relation to one another with their toe portions extending in 40 opposite directions and their central portions concealed, and a support extending upwardly from the bottom of the container for elevating the toe of the lower slipper to substantially the same level as the toe of the upper slipper.

45 2. A display container for slippers or the like having bottom and side walls, a longitudinal member secured intermediate its ends between the side walls and formed with oppositely extending tongues for receiving the toe portions of a pair of slippers and supporting said slippers with their toe portions extending in opposite directions, and a support extending upwardly from the bottom of the 50 container at each end thereof for raising the toes of the slippers to substantially the same level.

3. A display container for slippers or the like having bottom and side walls, a longitudinal member between the side walls and formed with oppositely extending tongues for receiving the toe portions of a pair of slippers and supporting said slippers with their toe portions extending in opposite directions, and a support at each end of said con-

tainer for raising the toes of said slippers, said support comprising an extension on the bottom of the container folded upwardly to a height below that of said side walls, and then folded downwardly and secured to the 70 bottom of the container.

4. A display container for slippers having bottom and side walls and a bridge portion connecting said side walls, a tongue of thin flexible material extending from each side of 75 said bridge portion between said side walls, each of said tongues being adapted to receive the toe portion of a slipper and thereby holding a pair of slippers in telescoped relation with their toes extending outwardly and a support for engaging the underside of the toe of the lower slipper for assisting the flexible tongue within said slipper in supporting the toe of the slipper at substantially the same level as the toe of the other slipper.

5. A display container for slippers or the like having bottom and side walls and a bridge portion connecting said side walls, a tongue of thin flexible material extending from each side of said bridge portion between said side walls, each of said tongues being adapted to receive the toe portion of a slipper and thereby hold a pair of slippers with their toes extending outwardly, and a support for engaging the underside of the toe portions of each 95 slipper for assisting said flexible tongues in supporting said toe portions at substantially the same level.

6. A display package for slippers or the like comprising a container having bottom 100 and side walls, a shoe tree of thin flexible sheet material having a pair of slippers thereon and disposed between said side walls, said pair of slippers being arranged in telescoping relation with their toe portions extending in 105 opposite directions and their central portions concealed by the central portion of the shoe tree, and a support extending upwardly from the bottom of the container for raising the toe of the lower slipper to substantially the 110 same level as that of the upper slipper.

7. A display container for slippers or the like comprising a body portion including side walls, a longitudinal member between said side walls and formed with oppositely extending tongues for receiving the toe portions of a pair of slippers and supporting said slippers with their toe portions extending in opposite directions, each of said tongues having curved side edges and provided with a plurality of 115 longitudinally arranged scorings outwardly curved on each side of the center of the tongue so that under pressure of the interior of the slipper said flexible tongues curve into arched form and serve to support substantially the 120 entire surface of the toe portions of the slippers.

8. A display container for slippers or the like having bottom and side walls and a bridge portion connecting said walls cen- 125

trally at the top thereof, a tongue of thin flexible material extending from each side of said bridge portion between said side walls and terminating substantially at the end of the container, each of said tongues being adapted to receive the toe portion of a slipper and thereby hold a pair of slippers with their toes extending outwardly, and a support at each end of said container for raising the toes of said slippers, said support comprising an extension of the material of the bottom of the container folded upwardly to a height below that of said side walls, and then folded downwardly and secured to the bottom of the container.

9. A display container for slippers or the like having bottom and side walls, a longitudinal member disposed between the side walls and formed with oppositely extending tongues for receiving the toe portions of a pair of slippers with their toe portions extending in opposite directions and their central portions concealed, and a support at one end of said container for raising the toe of the lower slipper to substantially the same level as the toe of the upper slipper, said support comprising an extension on the bottom of the container folded upwardly to a height below that of said side walls and then folded downwardly and secured to the bottom of the container.

10. A display container for slippers or the like, comprising a body portion including a bottom and side walls, a support extending upwardly from said bottom near one end thereof, and a shoe tree of thin flexible sheet material having a widened central portion for receiving a pair of slippers arranged in telescoping relation thereon with their toe portions extending in opposite directions and their central portions concealed by the central portion of the shoe tree, whereby when said slippers are disposed between said side walls the toe of the lower slipper will be raised by said support to substantially the same level as that of the upper slipper.

In testimony whereof I affix my signature.
LEO C. SAFIR.
